(57) **CLAIM**

The ornamental design for a door lever, as shown and described.

DESCRIPTION

FIG. 1 is a side perspective view of a door lever according to our new design.

FIG. 2 is a bottom view of the door lever as in FIG. 1.

FIG. 3 is a top view of the door lever as in FIGS. 1–2.

FIG. 4 is a front view of the door lever as in FIGS. 1–3.

FIG. 5 is a right side view of the door lever as in FIGS. 1–4.

FIG. 6 is a left side view of the door lever as in FIGS. 1–5; and,

FIG. 7 is a back view of the door lever as in FIGS. 1–6, the bottom is plane and unornamented.

The design of the present invention and as shown in FIGS. 1–7 is an ornamental door lever.
